2 SHEETS—SHEET 2.

UNITED STATES PATENT OFFICE.

THOMAS RUSSELL POST, OF WILMINGTON, NORTH CAROLINA.

DATING-STAMP.

1,032,769.

Specification of Letters Patent. Patented July 16, 1912.

Application filed December 8, 1911. Serial No. 664,570.

To all whom it may concern:

Be it known that I, THOMAS R. POST, a citizen of the United States, and residing at Wilmington, in the county of New Hanover and State of North Carolina, have invented certain new and useful Improvements in Dating-Stamps, of which the following is a specification, such as will enable those skilled in the art to which it appertains to make and use the same.

This invention relates to dating stamps of the class described and claimed in U. S. Letters Patent granted to me March 12, 1901, No. 669,661; and the invention consists in an improvement in stamps of this class whereby the construction thereof is rendered more simple and durable and less liable to get out of order and whereby the operation thereof is rendered more simple and effectual; and with these and other objects in view, the invention consists in a stamp of the class specified, constructed and operating as hereinafter described and claimed.

The invention is fully disclosed in the following specification, of which the accompanying drawing forms a part, in which the separate parts of my improvement are designated by suitable reference characters in each of the views, and in which:

Figure 1 is a side view of my improved dating stamp with part of the construction broken away; Fig. 2 a side view showing the parts in their normal position; Fig. 3 a transverse vertical section on the line 3-3 of Fig. 1; Fig. 4 a plan view of the printing wheels detached, together with the means by which they are rotated, and showing other parts of the construction; Fig. 5 a sectional plan view with part of the construction broken away; Fig. 6 a partial transverse section on the line 6-6 of Fig. 1; Fig. 7 a plan view of a detail of the construction shown in Fig. 6 and also shown in Figs. 1 and 2; Fig. 8 a transverse section of the inking rolls and the reservoir in which they are mounted and a sectional plan view of which is given in Fig. 5, and Fig. 9 a plan view of a sheet of paper showing an impression of my improved dating stamp.

In the practice of my invention I provide a base member *a* in the rear top portion of which is pivoted an arm *b*. In the form of construction shown, the base member *a* is also provided at its rear end with an upright support *a*² having a fork-shaped head *a*³ in

which the arm *b* is pivoted by means of a transverse pin *c* passed therethrough and through the head *a*³, and the arm *b* is also provided at its rear end with an opening *b*², 60 and wound on the pin *c* within the opening *b*² is a strong spring *d* one end *d*² of which bears on the bottom of the arm *b* and the other end *d*³ of which bears on the inner side of the upright support *a*².

The front end of the base *a* is provided with a raised member *a*⁴ having a head *a*⁵ on which is placed a plate or platen *a*⁶ on which the paper to be stamped is, in practice, placed, and the front end of the arm *b* is provided with a head *b*³ the top front portion *b*⁴ of which is formed separately and hinged to the bottom portion at *b*⁵ and the part *b*⁴ is provided with a raised supplemental head *b*⁶ by means of which the head of the arm *b* is depressed in operating the stamp as hereinafter described. The division line or plane between the head members *b*³ and *b*⁴ is a central horizontal plane or line *b*⁷, and formed partly in the bottom of 80 the head member *b*⁴ and partly in the head *b*³ is a circular chamber *b*⁸ which opens downwardly through the bottom of the head member *b*³ as clearly shown in Fig. 1, and passing centrally through the chamber *b*⁸ 85 transversely thereof is a spindle *e* having bearings formed partly in the head member *b*³ and partly in the head member *b*⁴, and removable when the head member *b*⁴ is raised or turned backwardly on the hinge 90 at *b*⁵.

Keyed to the inner end of the spindle within the chamber *b*⁸ is a month wheel *f* on which the names of the months are placed in any suitable type, and keyed to 95 the outer end of the spindle *e* is an operating disk *f*² by which said spindle and the month wheel *f* may be turned, and said month wheel is provided on its inner side with a ratchet portion *f*³ having spaced recesses *f*⁴, the position of which corresponds with the position of the separate months on the wheel *f*, and said operating disk *f*² has printed thereon in any way, the names 100 of the months so spaced as to correspond 105 with the names of the months on the wheel *f*.

Mounted on the spindle *e* is a sleeve *g* to the inner end of which is secured a day wheel *g*², and to the outer end of which is 110 secured an operating disk *g*³. The wheel *g*² is provided with type numbers representing

the days of a month and the operating disk g^3 is provided with corresponding numbers positioned in the same manner, and the wheel g^2 is provided with a ratchet 5 g^4 having spaced recesses g^5 the position of which corresponds with the position of the days of the month on said wheel.

Mounted on the sleeve g is a sleeve h to the inner end of which is secured a year 10 wheel h^2 having type representing the years, and said wheel is provided with a ratchet h^3 having recesses h^4 spaced to correspond with the position of the years on said wheel, and the outer end of the sleeve h 15 is provided with a disk h^5 which is keyed thereto and provided with numerals representing the years, positioned in the same manner as the type on the wheel h^2 .

Mounted on the sleeve h is a sleeve i 20 to the inner end of which is secured a utility wheel i^2 on which, in practice, may be placed any information such as paid, represented on the type wheel by the type letters "Pd"; or account, represented by 25 type letters "Act."; or O. K. as clearly indicated, or this wheel may be provided with type giving in any other form, any information desired, and said wheel is provided with a ratchet having spaced recesses 30 i^3 and the outer end of the sleeve i is provided with a disk i^4 which is secured thereto and on which is placed letters corresponding with the type on the wheel i^2 .

It will be observed that all the months, 35 days and years are not placed on the wheels f , g^2 , h^2 in the drawing and the disks i^4 , h^5 , g^3 and f^2 are also not provided with all the requisite letters or words, only enough being given in each case to indicate 40 the construction and use of these parts.

In the top part b^4 of the head of the arm b is a recess b^9 which communicates with the chamber b^8 and in the bottom of which is secured a transverse plate j having 45 spring fingers j^2 which operate in connection with or bear on the ratchets of the wheels f , g^2 , h and i and the ends of which are adapted to enter the recesses in said ratchets so as to regulate the movement of 50 said wheels and stop them at the desired point in the rotation thereof when said wheels are manipulated by the disks i^4 , h^5 , g^3 and f^2 .

In the bottom surface of the head member b^8 of the arm b at each side of the chamber b^4 are longitudinal recesses k in one of which is placed a removable business name die k^2 and in the other of which is placed a removable signature die k^3 and 55 these dies are held in place by gravity or other catches k^4 and when said dies are in position, the bottom surface thereof is flush with the corresponding surface of the wheels f , g^2 , h^2 and i^2 .

Arranged centrally of the top portion of

the base a is a cam block m the top surface of which is downwardly inclined as shown at m^2 and this cam block is adapted to enter a V-shaped recess m^3 in the bottom portion of the arm b .

The bottom central portion of the arm b is cut out on the opposite sides thereof, in the form of construction shown, to form longitudinal recesses m^4 and the central web member m^5 in the bottom of which is 70 a longitudinal recess m^6 which opens downwardly as clearly shown in Fig. 6, and the side walls of which are provided with longitudinal slots m^7 , and in the slots m^7 and passing through the longitudinal recess m^6 are pins n having anti-friction rollers n^2 , and the pins n pass through a hanger block n^8 movable longitudinally in the recess m^6 and the lower end of which is provided with an anti-friction roller n^4 adapted to 80 bear on the inclined surface m^2 of the cam block m , and said hanger block n^8 is provided with a backwardly directed pin n^5 which passes through a keeper n^6 secured to the bottom back part of the arm b , and between which and the hanger block n^8 is placed a strong spiral spring n^1 .

The block n^3 is provided with a forwardly directed yoke o between the separate side arms o^2 of which the cam block m is located, and the side arms o^2 of said yoke pass through keepers o^6 secured to the bottom of the front end portion of the arm b , and an inking reservoir p is connected with the front ends of the arms o^2 in any desired manner and provided with inking rollers p^2 . The inking reservoir p is provided with a cover p^3 through which the rollers p^2 project, and in the form of construction shown, the reservoir p is provided with transverse partitions p^4 whereby said reservoir is divided into separate compartments adapted to contain inks of different colors, and the rollers p^2 are correspondingly divided, whereby printing in different colors may be produced, but my invention is not limited to the exact construction of the reservoir p and rollers p^2 and any suitable devices of this class may be provided.

The parts b^8 and b^4 of the head of the arm b are provided with securing devices r by which they are connected and held in operative position, and it will be understood that any suitable device of this class may be employed, and in order to take out, repair or clean the working parts within the head b^8 — b^4 all that is necessary is to release the catch r and turn the head member b^4 backwardly, after which all the parts shown in Fig. 4 excepting the plate j and spring j^2 115 are lifted out, as will be readily understood, and said plate j may also be detached if desired.

From the foregoing description it will be seen that my improved dating stamp is a 120

self-inker, and the operation will be readily understood from the foregoing description when taken in connection with the accompanying drawing and the following statement thereof.

5 When the stamp is not in use, but ready for use, the arm *b* is normally held in the raised position shown in Fig. 2 by the spring *d* and when it is desired to stamp a sheet of paper, the said sheet, one of which is shown in Fig. 1 at *s* and also in Figs. 3 and 9, is inserted between the head *b*³—*b*⁴ and the platen *a*⁶ as shown in Fig. 1. The arm *b* is then depressed by striking the raised part *b*⁶ of the head member *b*⁴. This operation forces the head of the arm *b* downwardly into the position shown in Fig. 1 and the required date or other information is printed on the sheet *s* as shown in Fig. 9.

10 At the beginning of the downward movement of the arm *b* the inking device or reservoir *p* is moved backwardly by the hanger block *n*³ operating on the inclined surface *m*² of the cam block *m* and against the action of the spring *n*⁷ into the position shown in Fig. 1, and in this operation the wheels *f*, *g*², *h*² and *i*² or the type thereon is inked as will be readily understood, and when the force applied to the head of the 15 arm *b* is removed, the said arm is immediately thrown into the position shown in Fig. 2 by the spring *d* and the inking reservoir *p* is thrown into position for use, as shown in said figure, by the spring *n*⁷.

20 With the construction shown, the words "National air line" are printed on the paper *s* by the business name die *k*², while the words "John Doe" are printed thereon by the signature die *k*², the intermediate matter 25 including the month and day of the month, the year and the letters O. K. being printed by the wheels *f*, *g*², *h*² and *i*² and this matter may all be printed in black or any other solid color, or by dividing the inking reservoir 30 and rollers as described the matter may be printed in three separate colors.

25 It will be understood that the upward movement of the arm *b* is limited by the downwardly directed lug or projection *t* at the pivoted end of said arm, and by mounting the wheels *f*, *g*², *h*² and *i*² in the manner described and operating them by corresponding disks outside of the head of the arm *b* and providing the detachable signature dies and business name dies *k*² and *k*², I provide a simple and efficient construction which may be conveniently manipulated and which is extremely practical and effective in operation, and the improved arrangement whereby the printing wheels are manipulated by corresponding members outside of the head in which said wheels are placed gives to my improved dating stamp the greatest possible efficiency and simplifies 35 the manipulation and operation thereof to

an extent not heretofore known in other devices of this class.

Although I have shown and described the preferred form of my improvement, or the preferred means for carrying my invention 40 into effect, it will be understood that the said invention is not limited to the details of construction herein shown and described, and instead of the base *a* being made open, a suitable casing may be employed to inclose the cam block *m* if desired, together with parts connected with the arm *b* when depressed and various other changes therein and modifications thereof may be made, within the scope of the appended claims without departing from the spirit of my invention or sacrificing its advantages.

Having fully described my invention, what I claim as new and desire to secure by Letters Patent, is:—

35

1. A dating stamp comprising a base portion provided at one end with a platen, and an arm pivoted at the opposite end thereof, said arm being provided at its free end with a head divided horizontally into two parts, 40 one of which is hinged to the other, the parts of said head being provided with a chamber, rotatable printing wheels mounted in said chamber and removable therefrom, and an inking device supported beneath said arm 45 and movable longitudinally thereof and operated by the depression thereof.

2. A stamp of the class described provided with a pivoted arm having a head divided into top and bottom portions, the top portion being hinged to the back part of the bottom portion, and said head being provided with a chamber which opens downwardly therethrough, a spindle having bearings in the separate parts of said head and 50 removable therefrom and projecting therefrom, a plurality of printing wheels mounted on said spindle within said chamber and one of which is secured to the inner end of 55 said spindle and the others to concentric sleeves mounted thereon and projecting from said head, the outer end of said spindle and the outer ends of said sleeves being also provided with disks by which they may be rotated.

3. A stamp of the class described provided with a pivoted arm having a head divided into top and bottom portions, the top portion being hinged to the back part of the bottom portion, and said head being provided with a chamber which opens downwardly therethrough, a spindle having bearings in the separate parts of said head and removable therefrom and projecting therefrom, a plurality of printing wheels mounted on said spindle within said chamber and one of which is secured to the inner end of 100 said spindle and the others to concentric sleeves mounted thereon and projecting from 105 said head, the outer end of said spindle and the outer ends of said sleeves being also provided with disks by which they may be rotated.

110

4. A stamp of the class described provided with a pivoted arm having a head divided into top and bottom portions, the top portion being hinged to the back part of the bottom portion, and said head being provided with a chamber which opens downwardly therethrough, a spindle having bearings in the separate parts of said head and removable therefrom and projecting therefrom, a plurality of printing wheels mounted on said spindle within said chamber and one of which is secured to the inner end of 115 said spindle and the others to concentric sleeves mounted thereon and projecting from 120 said head, the outer end of said spindle and the outer ends of said sleeves being also provided with disks by which they may be rotated.

125

5. A stamp of the class described provided with a pivoted arm having a head divided into top and bottom portions, the top portion being hinged to the back part of the bottom portion, and said head being provided with a chamber which opens downwardly therethrough, a spindle having bearings in the separate parts of said head and removable therefrom and projecting therefrom, a plurality of printing wheels mounted on said spindle within said chamber and one of which is secured to the inner end of 130 said spindle and the others to concentric sleeves mounted thereon and projecting from said head, the outer end of said spindle and

the outer ends of said sleeves being also provided with disks by which they may be rotated, and said head being also provided in the bottom thereof and on the opposite sides of said wheels with detachable dies.

4. In a dating stamp, a base provided at one end with a platen, an arm pivoted at the opposite end of said base, and provided at its free end with a head having printing wheels, which operate in connection with said platen, and an inking device supported beneath said arm and movable longitudinally thereof, said device involving a spring

by which it is forced forwardly, and a hanger member movable longitudinally of said arm and operating in connection with a cam block mounted on the base to move it backwardly.

In testimony that I claim the foregoing as my invention I have signed my name in presence of the subscribing witnesses this 4th day of December 1911.

THOMAS RUSSELL POST.
